UNITED STATES PATENT OFFICE.

FRANK HAMACHEK, OF KEWAUNEE, WISCONSIN.

PEA-SEPARATOR.

1,304,765.

Specification of Letters Patent. Patented May 27, 1919.

Application filed August 20, 1915. Serial No. 46,445.

To all whom it may concern:

Be it known that I, FRANK HAMACHEK, a citizen of the United States, and resident of Kewaunee, in the county of Kewaunee and State of Wisconsin, have invented new and useful Improvements in Pea-Separators, of which the following is a description, reference being had to the accompanying drawings, which are a part of this specification.

10 This invention relates to pea separators which operate upon the crop of pea vines as harvested and by keeping the vines well separated and subjecting them to blows of rotating beaters causes the pods to break and liberate the green peas which are then sifted from the pods and vines and immediately discharged to avoid injury to them. The objects of the present invention are to improve upon details of construction of pea 20 separators generally and particularly of the pea separator construction illustrated and described in my application for pea hullers and separators which resulted in Letters Patent No. 1035184, dated Aug. 13, 1912.

25 One of the objects of the invention is to provide stationary discharging fingers at the discharge end of the sifter drum which extend downwardly and obliquely from the discharge opening of the drum in order to engage vines which may partially extend through the opening and thus coöperate with the turning of the drum in drawing vines out of the drum and preventing their accumulating at the discharge opening.

30 Another object of the invention is to provide a slotted, grooved chute leading from the discharge opening of the sifter drum with agitator wheels turning through the slots thereof to engage the tailings and lift 40 them and shake them while they are somewhat restrained in their travel by means of adjustable spring teeth above the chute and through this shaking and combing out operation effect the separation of such peas as 45 may have gone through the sifter drum with the tailings, the grooves of the chute affording a clear passageway for the discharge of such peas.

Another object of the invention is to improve upon details of construction of the tailings conveyer by means of which the tailings are discharged from the separator, whereby peas from the discharge chute and from the tailings may freely roll down the 55 tailings conveyer while the tailings are being lifted thereby.

Another object of the invention is to improve upon various details of construction of pea separators.

With the above and other objects in view 60 the invention consists in the pea separator as herein claimed and all equivalents.

Referring to the accompanying drawings in which like characters of reference indicate the same parts in different views: 65

Figure 1 is a central longitudinal sectional view of the discharge end of a pea separator constructed in accordance with this invention;

Fig. 2 is an end view thereof at the discharge end of the machine, parts being broken away for clearness of illustration; 70

Fig. 3 is a detail sectional view showing the construction of parts at the discharge end of the sifter drum; 75

Fig. 4 is a similar view at right angles to the view shown in Fig. 3;

Fig. 5 is a transverse sectional view of the discharge chute for tailings;

Fig. 6 is a sectional view showing the construction of the projecting teeth of the tailings conveyer belt; 80

Fig. 7 is a plan view thereof;

Fig. 8 is a view showing a modified form of tooth construction for the tailings conveyer belt, and; 85

Fig. 9 is a plan view thereof.

In these drawings 10 indicates a frame of any desirable construction which has a shaft 11 journaled through it in bearings 12. This 90 shaft carries a pulley 13 by means of which it may be driven from any suitable source of power. Between the bearings 12 the shaft has mounted on it a hexagonal or other desirably shaped body portion 14 provided 95 with hulling beaters 17 which may be variously shaped and are preferably oblique with relation to the axis of the body portion so that the turning movements of the shaft 11 cause them to act as propellers or 100 fan blowers for causing a current of air to flow in the direction of the rear or discharge end of the machine where the pulley 13 is located.

Surrounding the body 14 with its hulling 105 beaters is a sieve drum which has annular ends or heads 19 with metal bands or tracks 20 thereon which ride on rollers 21 on the frame to support the drum within the frame and permit it to rotate about the shaft 11 110 as its axis. A rotary movement is given to the drum by means of chains 22 which en-

gage occasional lugs or sprocket teeth 23 on the heads 19 of the drum and which chains also travel around sprocket wheels 24 on a countershaft 25 which is journaled at 5 the upper part of the frame and is driven from the shaft 11 by means of a sprocket wheel 26 on the shaft 25 connected by a chain 27 with a sprocket wheel 28 on said shaft 11. The direction of rotation of the 10 drum is the same as the direction of rotation of the hulling beaters, being the direction indicated by the arrow in Fig. 2, but its speed is much slower.

The end plates 44 at the ends of the drum 15 serve to confine the hulled peas to the space between them and fit close to the rings 19 as before and on the end plate 44 at the bottom of the discharge end of the sieve drum are secured a series of downwardly 20 extending oblique teeth 85 which are so arranged as to readily engage a projecting portion of a bunch of vines while being carried around with the drum and as these teeth are stationary they tend to hold the 25 vines while the drum turns away from them, thus assisting in the discharge of the vines from the drum. The teeth 85 being inclined are readily freed from the vines as the vines drop from the drum onto an inclined corrugated chute 86 below the teeth 85. The 30 downward movement of the vines on the inclined chute 86 is restrained somewhat by the presence of a stationary inclined rake 87 which is adjustably mounted on the frame 35 at 88 to be capable of having its position changed to suit the requirements. The tines of rake 87 project toward the corrugated inclined chute 86 and serve to hold the vines if they are in large masses and subject them 40 to the action of rotating combing wheels 89 therebeneath. The combing wheels 89 are mounted on a shaft 90 which is journaled across the discharge hopper 69 beneath the chute 86 and have backwardly turned arms 45 or fingers extending therefrom reaching through slots in the upper or crest portions of the corrugated surface of the inclined chute 86 as shown in Fig. 4. The action of these combing wheels 89 is to thoroughly 50 comb out and separate the bunches of vines which are sufficiently large to be engaged by the rake 87 and thus liberate the peas which may be entangled therein. Because of the corrugated surface of the inclined chute 55 86 the peas that are liberated readily separate from the tangled vines and pass down the trough portions of the corrugated surface. The inclined chute 86 discharges onto an inclined conveyer belt 91 which is in the 60 form of an apron of canvas or other suitable material having slats 92 extending across it on its bottom surface to keep it in shape without forming shoulders for engaging and holding the peas which are discharged there- 65 on by the inclined chute 86. In order that

the vines may not slide down the conveyer 91, however, the slats 92, have fingers 93 projecting upwardly from them through the apron and these fingers may be formed integral with metal slats as shown in Figs. 70 6 and 7 or they may be of sheet metal construction secured to wooden slats as shown in Figs. 8 and 9, or they may be of any other desirable construction. The fingers are preferably narrow so as not to present a surface 75 at their meeting edge with the apron which would serve to hold loose peas and carry them up with the conveyer, thus leaving the peas free to roll down the conveyer while the vines and other tailings are carried upwardly by the conveyer and discharged from the machine. The pulleys 94 at the upper and lower ends of the conveyer 91 are provided with grooves 95 to receive the slats 92 and thus permit of the apron being 80 85 kept tight at all times while also serving as a driving connection between the pulleys and the apron.

The operation of the pea separator of the present invention is substantially the same 90 as that of the structure covered by my co-pending application referred to. The peas liberated by the impact of the hulling beaters against the pods quickly find their way through the openings of the sieve drum 95 and roll down the inclined apron 47 to the conveyer 50. Such peas as may be contained in the tailings, however, are more effectively recovered as the vines are more quickly ejected from the sieve drum by their 100 engagement with the stationary teeth 85 and thus the tendency of the vines to bunch at the discharge end of the drum is prevented, and the action of the comb wheels 89 in co-operation with the retarding rake 87 serves 105 to entirely separate vines which may be tangled so that the peas held therein may be liberated and may pass down the grooves of the inclined chute 86 onto the apron of the conveyer 91, the construction of the conveyer being such that this separation of the 110 peas from the tailings is possible. While the vines are effectively carried upward by the conveyer 91 such conveyer presents no obstruction to the downward travel of the 115 peas thereon by reason of the slats being located beneath the apron and by reason of the shape of the fingers which present no surface against which the peas might lodge.

It may be found desirable when the vines 120 are heavy and wet to provide the chute 86 with guards as shown in Figs. 3 and 5 to hold the vines up off of the chute surface and assure free travel for the peas on the chute. The guards as shown consist of spring rods, 125 100, preferably attached at their upper ends to the underside of the chute and extending downwardly and forwardly at some distance above the chute. As stated the guards hold the vines away from the surface of the chute 130

allowing the combing wheels 89 to get better action on the vines, thus securing better separation of the peas from the vines than when the guards are not present.

5 What I claim as new and desire to secure by Letters Patent is:

1. In a pea separator, an inclined chute for conducting vine tailings having its surface corrugated to form inclined vine conducting ridges and troughs into which loose

10 peas may drop from the vines and be conducted separately from the vines.

2. In a pea separator, an inclined slotted chute for conducting vine tailings having 15 pea conducting surfaces between the slots, means for restraining the passage of masses of vines down the chute, and combing wheels beneath the chute having arms passing through the slots of the chute for separating

20 the vines held by the restraining means to release peas contained therein.

3. In a pea separator, an inclined slotted chute for conducting vine tailings having 25 pea conducting surfaces between the slots, an adjustable inclined rake positioned above

the inclined chute for restraining the passage of vines down the chute, and combing wheels beneath the chute having arms traveling through the slots of the chute for agitating and separating the vines held by the rake to release peas therefrom.

30 4. In a pea separator, an inclined chute

for conducting vine tailings and having a corrugated surface forming inclined troughs into which loose peas may drop and be conducted separately from the vines, said chute being provided with slots at the ridge portions of its corrugated surface, and combing wheels beneath the chute having arms traveling through the slots thereof for agitating 40 the vines in their travel to shake the peas therefrom.

5. In a pea separator, an inclined chute for conducting vine tailings and having its surface corrugated to form inclined troughs 45 into which loose peas may drop and be conducted separately from the vines, and inclined guard rods above the chute and approximately parallel therewith for holding masses of vines away from the surface of 50 the chute.

6. In a pea separator, an inclined chute for conducting vine tailings, and inclined parallel guard rods above the chute for lifting the vines therefrom and holding them away from the pea conducting surface of 55 the chute.

In testimony whereof, I affix my signature, in presence of two witnesses.

FRANK HAMACHEK.
